JAMES F. MARSHALL, OF WHITINSVILLE, MASSACHUSETTS, ASSIGNOR TO WHITIN MACHINE WORKS, OF WHITINSVILLE, MASSACHUSETTS, A CORPORATION OF MASSACHUSETTS

RING AND HOLDER FOR SPINNING AND TWISTING FRAMES

Application filed October 7, 1930. Serial No. 487,005.

This invention relates to spinning and twisting frames of the ring type and relates more particularly to the rings and ring holders used on such frames.

These rings are of two general types, those having horizontally disposed traveler flanges and those having vertically disposed flanges. These spinning and twisting rings are made of very hard and finely polished steel and 10 are commonly mounted in sheet metal holders which in turn are secured to the ring rails extending along the sides of the frame. Holes are bored in these ring rails so that the spindles and bobbins may be moved relatively upward and downward through the 15 rings to effect the winding of the yarn or thread thereon.

With the horizontal flange rings, the travelers do not extend down as far as the 20 ring rail and the holes in the rail need be only large enough to allow free passage of the bobbin and the thread thereon. With vertical flange rings, however, the lower flange commonly extends downward to or 25 below the top of the ring rail and the hole in the rail must be large enough to afford clearance for the lower portion of the flange and for the lower end of the traveler.

When vertical flange rings are substituted 30 for horizontal flange rings, it has been heretofore necessary to re bore the ring rails, which was an expensive operation and not always feasible, or to provide new rails at an even larger expense.

It is the general object of my invention to 35 provide means for securing a vertical flange ring in operative position on a ring rail without necessitating the enlargement of the holes therein previously provided for horizontal 40 flange rings. To the accomplishment of this result, I provide ring holders so designed that the lower flange of the ring is supported well above the ring rail, with the result that no 45 part of the ring or traveler can engage the ring rail.

My invention further relates to arrangements and combinations of parts which will be hereinafter described and more particularly pointed out in the appended claims.

A preferred form of the invention is shown in the drawings, in which

Fig. 1 is a plan view of a ring and holder embodying my invention;

Fig. 2 is a front elevation thereof;

Fig. 3 is a sectional front elevation thereof, taken along the line 3—3 in Fig. 1, and

Fig. 4 is a detail sectional elevation, taken along the line 4—4 in Fig. 1.

Referring to the drawings, I have shown 60 a portion of a ring rail 10 having the usual openings 11 formed therein, of such diameter as to be operative with a horizontal flange ring. I have also shown a vertical flange ring 12 of a usual commercial type and having a traveler T mounted thereon. 65

The ring 12 is supported by inserting the ring into an opening in a ring holder 20 until a flange 21 on the ring engages the top 70 surface of the holder.

Ears 22 (Fig. 4) are preferably struck up from the top portion of the holder and firmly engage the upper edge of the flange 21 on the ring, preventing displacement thereof.

To avoid the necessity of enlarging the holes 11 to provide clearance when changing from horizontal to vertical type rings on the same frame, I provide my improved ring holder with downwardly offset supporting portions 23 having base portions 24 adapted to be secured to the rail 10 by the usual clamping screws 25.

With this construction, all parts of the ring 12 and traveler T are supported well 80 above the upper surface in the rail 10 and there is ample clearance for the traveler T.

I am thus able to change over a spinning or twisting frame from horizontal to vertical flange rings, simply by loosening the screws 90 25, removing the flat ring holders with the horizontal flange rings, and applying my improved ring holders with the vertical flange rings in raised position.

It is thus possible to change a frame from 95 horizontal to vertical type rings at a slight expenditure of time and labor and without moving the ring rails from the frame or performing any mechanical operations thereon. The changing of frames from one type of 100

rings to the other is thus greatly simplified and may be readily accomplished at any time and as often as desired.

Having thus described my invention and the advantages thereof, I do not wish to be limited to the details herein disclosed, otherwise than as set forth in the claims, but what I claim is:—

1. In a ring spinning frame having a ring rail, a vertical flange ring having a supporting portion and having a traveler flange extending substantially above and below said supporting portion, a traveler for said ring having portions embracing the upper and lower edges of said traveler flange, and a sheet metal holder for said vertical flange ring comprising a body portion apertured to receive the lower portion of the vertical flange of said ring and oppositely disposed and downwardly offset projecting portions directly engaging the ring rail and supporting the body portion and ring spaced sufficiently above the rail to elevate all portions of the ring substantially above the ring rail and to provide substantial clearance between the lower portion of the traveler and the ring rail, said traveler being also entirely clear of all parts of said holder.
2. In a ring spinning frame having a ring rail, a vertical flange ring having a supporting portion and having a traveler flange extending substantially above and below said supporting portion, a traveler for said ring having portions embracing the upper and lower edges of said traveler flange, and a holder for said vertical flange ring comprising a body portion apertured to receive the lower portion of the vertical flange of said ring and having downwardly and outwardly projecting portions directly engaging the ring rail and supporting the body portion and ring spaced sufficiently above the rail to elevate all portions of the ring substantially above the ring rail and to provide substantial clearance between the lower portion of the traveler and the ring rail, said traveler being also entirely clear of all parts of said holder, and said projecting portions being adapted to be secured at spaced points to said ring rail.

In testimony whereof I have hereunto affixed my signature.

JAMES F. MARSHALL.
